H. MARGULIES.
LOCK.
APPLICATION FILED SEPT. 9, 1920.

Patented Jan. 18, 1921.

UNITED STATES PATENT OFFICE.

HARRY MARGULIES, OF NEW YORK, N. Y.

LOCK.

1,365,714.

Specification of Letters Patent. Patented Jan. 18, 1921.

Application filed September 9, 1920. Serial No. 409,083.

To all whom it may concern:

Be it known that I, HARRY MARGULIES, a citizen of Poland, residing at New York city, county and State of New York, have invented certain new and useful Improvements in Locks, of which the following is a full, clear, and exact description.

This invention relates to improvements in locks, more particularly pad-locks, one of the objects being to provide a lock of this nature that cannot be easily picked or operated without an especially arranged key. Other features of improvement will hereinafter appear.

I will now proceed to describe my invention in detail, the novel features of which I will finally claim, reference being had to the accompanying drawing, forming part hereof, wherein:

Figure 1 illustrates my improved lock in elevation;

Fig. 2 is a sectional plan view thereof, the section being taken on a line 2—2 in Fig. 3;

Fig. 3 is an enlarged vertical sectional view, the section being taken on a line 3—3 in Fig. 2;

Fig. 4 is an enlarged vertical sectional view of the key;

Fig. 5 is a fragmentary sectional view of a portion of the tumbler mechanism; and

Fig. 6 is a fragmentary sectional diagrammatic view illustrating the application of the key to the lock.

My improved lock is made up of a casing or barrel portion 7, which contains the lock mechanism, a shackle member 8, consisting of leg members 9 and 10 connected at one end, as at 11, means to lock the shackle member, and a key 12 to operate the mechanism for actuating certain elements or tumblers to lock the shackle against movement or withdrawal from the barrel.

It will be seen that the leg members 9 and 10 are not of the same length, the member 9 being the longer and slidably supported by a tubular pillar 13 located between disks 14 and 15. The disks 14 and 15 are connected and maintained, separated by means of post members 16, 17 and 18. As will be seen the leg 9 of the shackle passes through an opening 19 in the disk 14, said opening alining with the bore of the tubular pillar 13. The opening 19 is somewhat smaller in diameter than the bore of said pillar to provide an abutment 19^a for a collar 20 carried by the leg 9, at its lower end. A spring 21 within

the pillar 13 tends to force the shackle upwardly, but said shackle cannot be forced out of the pillar owing to the provision of said abutment 19^a and collar 20. The leg-member 10, of the shackle extends through an opening 22 in a head-plate 23 when said shackle is locked. The head-plate 23 is secured to the barrel 7 by means of screws 24 or otherwise. The leg-member 9 of the shackle passes through an opening 25 in the head-plate 23. The shackle 8 is locked or held in depressed position by means of a tumbler or latch 26 carried by a tubular post 27 rotatably supported by the disks 14 and 15. The latch or tumbler 26 engages a notch 28 in the shackle leg-member 9. The latch or tumbler 26 is in turn operated by means of an arm 29 carried by a pin 30 slidably supported by the post 27. The pin 30, at its lower end, is bifurcated as at 31 to engage a plate 32 slidably supported in slots 33 formed in the post 27, adjacent to the upper end thereof. The pin 30 is arranged to be moved vertically against the tension of a spring 34 to elevate the arm 29 to cause the pin 35 carried thereby to become disengaged from an opening 36 in the disk 14, said pin freely passing through an opening 37 in the latch or tumbler 26. When arm 29 is in depressed position, (see Fig. 3), the pin 35 will be engaged with opening 36; hence latch 26 cannot be moved out of notch 28 and the shackle cannot be raised to cause the short leg 10 to clear head-plate 23. The latch is maintained in engagement with said notch by a spring 38 carried by a plate 39 pivotally supported in this instance, by post 18. The tension of spring 38 is maintained by said plate 39 which at its free end bears against the casing 7 when the mechanism is in position within the casing. The tubular post 27 carries a slidable pin 40 which is maintained in depressed position by a spring 41, said pin sliding within a reduced portion 41^a of the bore of the post, said bore being provided with a slot 42 to receive the latch 43 of the key 12. The key 12 consists of a tubular member 44 carrying a fixed post 45, surrounded by a spring 46. The post 45 is tubular and pivotally supports the latch 43 which is normally pressed outwardly by a spring 48. To unlatch the shackle, the tubular member 44 will be inserted through the opening 49 in the bottom of the casing and over the

tubular post 27 and forced upwardly in contact with a slidable sleeve 50 on said post 27. A further upward movement will force sleeve 50 upwardly into contact with 5 the head 51 on plate 32, and finally will move arm 29 upwardly (see dotted lines Fig. 5), thereby withdrawing pin 35 from opening 36. At about this time, latch 43 will engage slot 42 in post 27, after which 10 the key can be rotated, causing latch 26 to leave slot 28. The shackle will now be in condition to be raised to become disengaged from any element to which it is attached. When the tubular body member 44 of the 15 key is forced upwardly over the post 27, spring 46 in the tubular member 44 will be compressed, thereby permitting the fixed tubular post 45 to force pin 40 upwardly to uncover the slot 42 (see Fig. 6). When 20 the key is withdrawn springs 34 and 41 will restore the respective parts to normal position. To lock the shackle it is first necessary to force it downwardly, after alining the short leg 10 and opening 22 to cause 25 notch 28 to aline with latch 26, whereupon the spring 38 will force the said latch into said notch and lock the shackle.

Having described my invention, what I claim is:

- 30 1. In a lock, a casing, a shackle carried thereby, a pivotal locking latch to engage the shackle, means to lock the latch against movement when in engagement with the shackle and a tubular key arranged to be inserted into said casing to actuate the latch locking means to release the latch and also to move the latch upon its pivot to unlocked position after said latch has been released.
2. In a lock, a casing, a shackle carried 40 thereby, a tubular oscillatable post within the casing, a latch carried thereby arranged to engage said shackle, means adjacent the latch arranged to lock the latch against movement when it is in engagement with the shackle, a tubular key arranged to be slipped over said post, and means carried by the key to engage said post and rotate same, said key being arranged to release the latch locking means.
- 50 3. In a lock, a casing, a shackle carried thereby, a tubular oscillatable post within the casing, a latch carried thereby arranged to engage said shackle, an arm superimposed upon said latch, said arm being slidably supported, in a vertical plane, by said tubular

post, means carried by the arm to engage the latch and lock same against movement, a tubular key to engage said post and partly rotate same to cause said latch to become released from said shackle, said key being also 60 arranged to actuate said arm to release said latch before said post is operated.

4. In a lock, a casing, a shackle carried thereby, a movable post within the casing, a latch carried thereby to engage said shackle 65 and lock same against movement, means to lock the latch against movement when in engagement with said shackle, and a key arranged to engage said post and operate same to cause said latch to become disengaged from said shackle, said key being also 70 arranged to operate the latch locking means before the said post is operated.

5. In a lock, a casing, a shackle carried thereby, a tubular oscillatable post within 75 the casing, a latch carried thereby arranged to engage said shackle, an arm superimposed upon said latch, said arm being slidably supported, in a vertical plane, by said tubular post, means carried by the arm to engage 80 the latch and lock same against movement, a pin slidably mounted within said post, said post having a slot normally covered by said pin, a key consisting of a tubular body member arranged to be slipped over said post 85 and moved longitudinally thereof, means carried by the post to coöperate with said key to actuate said latch-locking means, means carried by said key body member to move the pin within said post to uncover 90 the slot therein when said key is moved along said tubular post sufficiently to release said latch locking means, and means carried by the key body member to engage the slot in the tubular post whereby said post may 95 be partly rotated to release said latch.

6. In a lock, a casing member, a shackle member, a support therefor, a movable latch, a releasable locking pin to engage the latch and the support for the latch to lock the 100 latch against movement, and a key member arranged to first move the locking pin out of engagement with the support for the latch and then to operate the latch.

Signed at New York city, N. Y., this 7th 105 day of September, 1920.

HARRY MARGULIES.
